UNITED STATES PATENT OFFICE.

JOHN BATH AND ROBERT H. C. GRUNEWALD, OF WORCESTER, MASSACHUSETTS, AS
SIGNORS TO JOHN BATH & CO. INC., A CORPORATION OF MASSACHUSETTS.

ADJUSTABLE INTERNAL GAUGE.

Application filed October 27, 1919. Serial No. 333,651.

To all whom it may concern:

Be it known that we, JOHN BATH and ROBERT H. C. GRUNEWALD, citizens of the United States, both residing at Worcester, 5 in the county of Worcester and State of Massachusetts, have invented a new and useful Adjustable Internal Gauge, of which the following is a specification.

This invention relates to improvements in 10 an internal adjustable gauge of the type shown in the prior application of John Bath and Walter E. Gray, Serial No. 300,053, filed May 27, 1919.

One object of our present invention is to 15 provide improved means for locking the gauge in a predetermined or zero position. Another object is to provide an improved device for clamping the gauge in any desired position. Further objects of our invention are to provide means for protecting 20 the operating screw from dirt and injury and also for protecting the centers and preserving their accuracy.

Our invention further relates to arrangements and combinations of parts herein- 25 after described and more particularly pointed out in the appended claims.

A preferred form of our invention is 30 shown in the drawings, in which—

Fig. 1 is a longitudinal sectional elevation 35 of our improved gauge;

Fig. 2 is an end view thereof;

Fig. 3 is a transverse sectional view taken 40 along the line 3—3 in Fig. 1;

Fig. 4 is a detail plan view of portions 45 of certain parts, and

Fig. 5 is a detail plan view of certain parts.

Referring to the drawings, our improved 50 gauge comprises a body 10 having an enlarged end portion or flange 11. A threaded rod 12 has a bearing in the body 10 and is provided with a shoulder 13 engaging an internal flange 14 of the body 10, by which 55 axial movement of the rod 12 in one direction is prevented.

An adjustable member or head 15 is 60 threaded on the rod 12, and is moved axially when the rod 12 is rotated. The head 15 is provided with a plurality of dove-tailed 65 tapered guide-ways 16 (Fig. 3) within which tapered gauge bars 17 are slidably mounted. The gauge bars are held from axial movement 70 by engagement with the flange 11 at

one end and with a collar 18 at the opposite 55 site end.

At least one of the gauge bars 17^a is 60 preferably slotted radially at each end as indicated at 19 and 20 at Fig. 1. A key 21 mounted in the flange 11 extends into the slot 19 and a similar key 22 mounted in the collar 18 extends into the slot 20. The gauge-bar 17^a is thus held for radial movement only and itself limits the movement of each of the other gauge-bars to radial movement only, as the bars are all held in spaced relation in the head 15.

The collar 18 is mounted on a sleeve 23 65 which in turn is slidable on a reduced end portion 2^a of the threaded rod 12, to which 70 it is keyed. A nut 24 is mounted on a threaded outer portion 25 of the rod 12 and acts against a washer 26 which in turn engages an inner shoulder on the sleeve 23. A check nut 27 locks the nut 24 in adjusted 75 position and also extends beyond the end of the threaded portion 25 of the rod 12, thus preventing accidental injury of the center hole therein. By means of the nuts 24 and 27, the collar 18 may be adjusted to take up 80 all back-lash at the ends of the gauge bars 17.

An additional collar or ring 28 is mounted 85 on the outer end of the sleeve 23 and may be secured in adjusted position thereon by a set-screw 29. As the collar 28 rotates with the threaded rod 12 and the collar 18 is relatively stationary, we provide graduations 30 upon the collar 18 and a zero mark 31 on the collar 28 by which gauge readings 90 may be obtained. The gauge may be set to any desired size, after which the zero mark 31 may be brought to correspond with the zero of the graduations 30 and the graduations will then indicate variations above or 95 below the desired size.

It is to be noted that the inner portion 32 of the sleeve 23 extends into a recess 33 in the outer end of the head 15, while an extension 34 on the head 15 similarly extends 100 into a recess 35 in the end of the body 10. These extended portions protect the thread of the rod 12 from injury in every position of the head 15.

A portion of the thread in the head 15 is 105 formed on a collar 36 which in turn is threaded into the head 15 but with a thread of a different pitch. By slightly turning

the collar 36, which is provided with a suitable screw-driver slot, any looseness between the head and the threaded rod 12 may be taken up. The collar 36 may be held in 5 adjusted position by a set-screw 37.

It is desirable to provide a stop by which the gauge may be quickly set to a selected standard size, and for this purpose we provide a sleeve 38 fixed in the body 10 by a 10 stud or screw 39, and providing a bearing for an extension 40 of the threaded rod 12.

The sleeve 38 is provided with a slot 41 (Fig. 4) to receive a lug 42 formed on the end of a second sleeve 43 keyed at 40° to the 15 extension 40 of the threaded rod 12 and slideable thereon. Outward movement of the sleeve 43 is limited by a nut 44 threaded on the extension 40 and also serving to protect the center from injury. The outer portion of the sleeve 43 may be knurled to provide a convenient part by which the threaded rod 12 may be turned.

When the sleeve 43 is in the position shown in Fig. 1 the rod 12 may be freely 25 turned, but if it is desired to lock the gauge in a fixed position the sleeve is pushed inward until the lug 42 enters the slot 41.

In assembling the gauge, the gauge-bars 17 are first finished by grinding and polishing and are then set to a standard ring gauge before the hole for the stud 39 is drilled in the collar 38. The sleeve 43 is then pushed inward to engage the slot in the collar 38. The hole is then drilled and the stud 39 is 30 inserted. It follows that whenever the parts are returned to this position the gauge will indicate the original standard size.

In order to read directly the exact size to which the gauge is set, it is necessary to 40 employ a set of graduations additional to those shown on the collar 18, as the latter graduations commonly represent merely sub-divisions of one one-hundredth of an inch.

Accordingly we provide an index or zero mark 45 on one of the gauge bars as 17° (Fig. 1) and I provide cooperating graduations 46 (Fig. 5) on the head 15, one of these graduations being marked with the 50 nominal size of the gauge. Preferably the graduations 46 are formed on a plate 47 having a ledge or rib 47° at one edge slideable in a slot in the head 15. The plate 47 is secured in adjusted position by screws 48 55 extending through elongated openings 49 in the plate 47 and binding the plate to the head 15. When the bars 17 become worn and are re-ground the relative position of the head 15 for a given standard size is 60 changed, but the provision of the adjustable plate 47 permits the scale to be adjusted to again indicate the correct size after each re-grinding.

We have also provided improved means 65 to clamp the threaded rod 12 in any desired

position to preserve any setting of the gauge. For this purpose we provide two radial openings 50 in the body 10 within which are slidably mounted plugs 51 having inclined outer end surfaces. The plugs 51 are engaged by the clamping nut 52 threaded to the end of the body 10 and having an internal conical surface 53 adapted to force the plugs 51 radially inward against the surface of the sleeve 43 which in turn is 75 keyed to the extension 40 of the rod 12.

Having thus described our invention, it will be evident that we have provided an adjustable internal gauge embodying desirable and novel features of construction, 80 and it will also be evident that changes and modifications can be made in our invention within the spirit and scope thereof as set forth in the claims. Therefore we do not wish to be otherwise limited to the details 85 herein disclosed but what we claim is:—

1. An adjustable internal gauge comprising a body, a threaded rod rotatable therein but held from axial movement relative thereto, a plurality of gauge bars having faces 90 inclined to the longitudinal axis of said rod, an adjusting member threaded on said rod and slidably supporting said bars, said member having inclined faces cooperating with the inclined faces of said gauge bars to adjust them radially when said member is moved axially of said rod and longitudinally of said gauge bars, a sleeve fixed in said body, and a second sleeve mounted on said rod and axially movable thereon but held from angular movement relatively thereto, said sleeves having cooperating portions which, when brought into engagement by axial movement of one of said sleeves, prevent angular movement of said rod relative 95 to said body.

2. An adjustable internal gauge comprising a body, a threaded rod rotatable therein but held from axial movement relative thereto, a plurality of gauge bars having faces 110 inclined to the longitudinal axis of said rod, an adjusting member threaded on said rod and slidably supporting said bars, said member having inclined faces cooperating with the inclined faces of said gauge bars to adjust them radially when said member is moved axially of said rod and longitudinally of said gauge bars, and means to lock said rod in predetermined angular relation to said body, positively preventing further 115 relative angular movement thereof.

3. An adjustable internal gauge comprising a body, a threaded rod rotatable therein but held from axial movement relative thereto, a plurality of gauge bars, an adjustable member threaded on said rod and slidably supporting said bars, and means to hold 125 said rod in adjusted position, said means including radially movable clamping members and a clamping nut having an internal 130

conical surface effective to engage said members and force them inward to clamping position.

4. An adjustable internal gauge comprising a body, a threaded rod rotatable therein but held from axial movement relative thereto, a plurality of gauge bars having faces inclined to the longitudinal axis of said rod, an adjusting member threaded on said rod and slidably supporting said bars, said member having inclined faces cooperating with the inclined faces of said gauge bars to adjust them radially when said member is moved axially of said rod and longitudinally of said gauge bars, and a sleeve having a bearing in said body and mounted on said rod for axial movement only relative to said rod, said body having radial openings therein, and having clamping plugs slidable in said openings and engaging said sleeve, and means being also provided to force said plugs inward against said sleeve to clamp said rod in adjusted angular position in said body.

5. An adjustable internal gauge comprising a body, a threaded rod rotatable therein but held from axial movement relative thereto, a plurality of gauge bars having faces inclined to the longitudinal axis of said rod, and an adjusting member threaded on said rod and slidably supporting said bars, said member having inclined faces cooperating with the inclined faces of said gauge bars to adjust them radially when said member is moved axially of said rod and longitudinally of said gauge bars, said member having an extension and said body having a recess within which said extension is received, said extension covering and protecting the threaded rod as said member is moved away from said body.

6. An adjustable internal gauge comprising a body, a threaded rod rotatable therein but held from axial movement relative thereto, a plurality of gauge bars having faces inclined to the longitudinal axis of said rod and an adjusting member threaded on said rod and slidably supporting said bars, said member having inclined faces cooperating with the inclined faces of said gauge bars to adjust them radially when said member is moved axially of said rod and longitudinally of said gauge bars, a bar retaining sleeve mounted on the gauge end of said rod for axial movement only relative thereto, and means to adjust and secure said sleeve in desired axial position on said rod.

7. An adjustable internal gauge comprising a body, a threaded rod rotatable therein but held from axial movement relative thereto, a plurality of gauge bars having faces inclined to the longitudinal axis of said rod, an adjusting member threaded on one end of said rod and slidably supporting

said bars, said member having inclined faces cooperating with the inclined faces of said gauge bars to adjust them radially when said member is moved axially of said rod and longitudinally of said gauge bars, a retaining sleeve mounted on the end of said rod adjacent said gauge bars for axial movement only relative thereto, means to adjust said sleeve axially and to secure said sleeve in adjusted axial position on said rod, and means to indicate the adjusted angular position of the sleeve.

8. An adjustable internal gauge comprising a body, a threaded rod rotatable therein but held from axial movement relative thereto, a plurality of gauge bars having faces inclined to the longitudinal axis of said rod, an adjusting member threaded on one end of said rod and slidably supporting said bars, said member having inclined faces cooperating with the inclined faces of said gauge bars to adjust them radially when said member is moved axially of said rod and longitudinally of said gauge bars, a retaining sleeve mounted on the end of said rod adjacent said gauge bars for axial movement only relative thereto, a recessed adjusting nut for said sleeve, and a lock nut in the recess of said adjusting nut.

9. An adjustable internal gauge comprising a body, a threaded rod rotatable therein but held from axial movement relative thereto, a plurality of gauge bars having faces inclined to the longitudinal axis of said rod, an adjusting member threaded on one end of said rod, and slidably supporting said bars, said member having inclined faces cooperating with the inclined faces of said gauge bars to adjust them radially when said member is moved axially of said rod and longitudinally of said gauge bars, a bar retaining sleeve mounted on the end of said rod adjacent said gauge bars for axial movement only relative thereto, a recessed adjusting nut for said sleeve, and a lock nut in the recess of said adjusting nut, said lock nut extending beyond the end of said rod and protecting the center therein from injury.

10. An adjustable internal gauge comprising a body, a threaded rod rotatable therein but held from axial movement relative thereto, a plurality of gauge bars having faces inclined to the longitudinal axis of said rod, an adjusting member threaded on said rod and slidably supporting said bars, said member having inclined faces cooperating with the inclined faces of said gauge bars to adjust them radially when said member is moved axially of said rod and longitudinally of said gauge bars, said member and one of said bars having parts carrying cooperating graduations, and means permitting relative adjustment of the parts carrying said graduations.

11. An adjustable internal gauge comprising a body, a threaded rod rotatable therein but held from axial movement relative thereto, a plurality of gauge bars having faces inclined to the longitudinal axis of said rod, an adjusting member threaded on said rod and slidably supporting said bars, said member having inclined faces cooperating with the inclined faces of said gauge bars to adjust them radially when said member is moved axially of said rod and longi-

tudinally of said gauge bars, one of said gauge bars having an index thereon, a graduated plate mounted on said head and cooperating with said index to designate 15 gauge diameter, and means permitting relative axial adjustment of said plate on said head.

In testimony whereof we have hereunto affixed our signatures.

JOHN BATH.

ROBERT H. C. GRUNEWALD.
